UNITED STATES PATENT OFFICE.

JAMES HENRY GREGORY AND MIRL LEO SIAS, OF FARWELL, MICHIGAN.

WIRE-TIER FOR BALING-MACHINES.

No. 911,391.

Specification of Letters Patent.

Patented Feb. 2, 1909.

Application filed September 11, 1908. Serial No. 152,843.

To all whom it may concern:

Be it known that we, JAMES HENRY GREGORY and MIRL LEO SIAS, both citizens of the United States, and residents of Farwell, in 5 the county of Clare and State of Michigan, have invented a new and Improved Wire-Tier for Baling-Machines, of which the following is a full, clear, and exact description.

This invention relates to certain improvements in mechanism for tying the wire about 10 bales of any suitable material, as, for instance, hay or straw.

The object of the invention is to avoid 15 the necessity for using wire with a special head or loop, and to firmly secure together the plain overlapping ends of ordinary wire, the fastening operation being brought about by the movement of the material within the baling press.

20 Reference is to be had to the accompanying drawings, forming a part of this specification, in which similar characters of reference indicate corresponding parts in all the figures, and in which—

25 Figure 1 is a front view of a baling press provided with our improved mechanism; Fig. 2 is an inverted plan view thereof; Fig. 3 is a side elevation of the transverse tying bar, a portion thereof being broken 30 away; Fig. 4 is a longitudinal section through one of the wire tiers; Fig. 5 is a detail showing the releasing mechanism; and Fig. 6 is an end view of a portion of one of the tying wheels.

35 In the drawings, there is illustrated a baling press having parallel bottom and top walls 10 and 11, a side wall 12, an end wall 13, and a movable presser head or follower 14. One side of the press is open, and 40 across this open side extends our improved tying mechanism. The tying mechanism *per se* includes two oppositely-disposed substantially parallel bars or plates 15 and 16, between which are journaled a series of in-

45 termeshing gear wheels 17, 18, 19, 20 and 21, the number of gear wheels depending upon the number of wires to be tied. Each alternate wheel 17, 19, and 21, constitutes a tying wheel, while the intermediate wheels 18 and 50 20 serve merely to transmit motion from one tying wheel to the next. Each of the tying wheels 17, 19 and 21 is mounted on an axle 22 extending through the side plates 15

and 16, and each wheel is provided with a radial slot 23 extending inwardly from its circumference to its axle. Each axle 22 is provided with a corresponding slot in alignment with the slot 23, and both of these slots are of a width slightly greater than the diameter of the wire to be tied or twisted. A portion of the slot in the axle intermediate the ends of said axle may be of a width substantially equal to the diameter of the wire, so as to firmly grip the latter and preclude the possibility of the two wires 60 passing each other within the slot. The intermediate motion-transmitting wheels 18 and 20 may be of any suitable character and mounted in any suitable way so as to intermesh with the adjacent tying wheels. 70

Adjacent each tying wheel is a U-shaped gripping member 24, having its opposite ends extending downwardly substantially parallel to the side plates 15 and 16 but spaced a short distance therefrom and having its intermediate portion flattened and rigidly secured to the upper edges of said supporting plates. Each end of the gripping member terminates in a fork 25, the slot 26 between the tines of which is of width 80 substantially equal to the diameter of the wire. The outer end of the slot 26 comes adjacent the lower edges of the plates 15 and 16, while the upper or inner end of each slot 26 comes substantially in alignment with 85 the center of the corresponding shaft 22. For tying together two wire ends, the latter are inserted through the forks and through the registering slots when the latter are in the positions indicated in Figs. 3 and 4. By 90 rotating the tying wheels, the portions of the wires within the narrowest portion of the slot of the wheel are twisted about each other, but the portions of the wires within the forks 25 are prevented from twisting, 95 so that the two wires become firmly interlocked, as indicated in Fig. 4. The wires cannot leave the slots save when the slot of the wheel is in alignment with the slots of the side plates and the slots of the forks. 100

For mounting and operating our improved tying mechanism, the two side plates 15 and 16 are connected together at one end and provided with a wheel 27 lying in a plane at right angles to the planes of said 105 plates and adjacent their inner edges. This

wheel 27 is adapted to run along a track or rail 28 secured adjacent the top wall 11 of the press. Within the opposite wall of the press, we mount a spur wheel 29, the 5 points of which extend into the press, so as to rotate the wheel by the movement of the material being baled, as the presser head or follower is forced longitudinally. The wheel 29 is mounted upon a shaft 30 and at 10 the front end of the shaft is a bevel gear 31 for transmitting motion to a bevel gear 32 on a shaft 33 extending longitudinally of the press. The shaft 33 is so mounted that one end thereof may be moved laterally a 15 short distance, and the shaft is provided with a keyway extending longitudinally thereof, so that it may rotate a gear wheel 34, as the latter slides along the shaft. This gear wheel is adapted to engage with the 20 end tying wheel 21, so as to rotate all of the tying wheels by the movement of the hay or other material in the portion of the press adjacent the follower. For causing a similar movement of the tying mechanism as the 25 material becomes compressed into a smaller space, the side plates 15 and 16 may be provided with depending points or projections 35, which may engage with the material being baled and cause the tying mechanism to 30 move along the track 28.

For releasing the tying mechanism, the shaft 33 is so mounted that one end may be moved laterally to bring the gear wheel 34 out of mesh with the tying gear wheel 21. 35 As indicated, the shaft is provided with a collar 36 having a pivoted hook or projection 37 which normally engages with a shoulder or projection 38 on the side wall 10, to hold the shaft 33 against lateral movement. The side plate 16 of the tier is provided with a projection 39, which is adapted 40 to engage with the hook 37 and force it out of engagement with the shoulder 38 and permit the shaft to swing laterally to the 45 position indicated in Fig. 5, to bring the gear wheel out of mesh with the tying gear wheel 27. For swinging the tying mechanism out of engagement with the material being baled, so that it will no longer advance therewith, the bottom wall 10 of the 50 press carries a cam 40, which upon engagement with the under side of the tying mechanism, swings the latter outwardly.

During the movement of the tying mechanism along the baling machine, the flange on the wheel 34 engages with the side of the end wheel 21 and the two are kept in engagement with each other. As soon as the shaft is moved laterally to the position indicated in Fig. 5, the spring connected to the gear 34 draws the latter longitudinally of the shaft toward the presser head 14.

After the tying operation has been com-

pleted and the wires are removed from the tying mechanism, the slight looseness will 65 be taken up by the expansion of the baled material after the removal of the latter from the baling press.

Having thus described our invention, we claim as new and desire to secure by Letters 70 Patent:

1. A wire tier for baling presses, including a member extending transversely of the press and supporting a plurality of intermeshing wheels rotatable in a plane at 75 right angles to the length of the press, certain of said wheels serving to twist together overlapping wire ends and the remaining wheels serving to transmit motion from one wire-twisting wheel to the next, a shaft extending longitudinally of the press, means for rotating said shaft, and a gear wheel carried thereby and movable into or out of mesh with one of the wheels carried by 80 said transversely-extending member. 85

2. A wire tier for baling presses, comprising a member extending transversely of the press and supporting a plurality of intermeshing wheels rotatable in a plane at right angles to the length of the press, certain of said wheels serving to twist together overlapping wire ends, a shaft extending longitudinally of the press, means for rotating said wheels by the rotation of said shaft, means for rotating said shaft during 95 the baling action, and means for moving said transversely-extending member longitudinally of the press during the baling action.

3. A wire tier for baling presses, comprising a member extending transversely of the press, means carried thereby for twisting together the overlapping wire ends, a shaft extending longitudinally of said press, means for rotating said shaft during the baling action, a gear wheel carried by said 100 shaft for transmitting motion from the latter to the wire-twisting means, and means for automatically moving said shaft laterally to bring said gear wheel to inoperative 105 position. 110

4. A wire tier for baling presses, including a plurality of wire-twisting wheels disposed in a plane transversely of the length of the press and each movable longitudinally of the press, a spur wheel extending 115 through one wall of the press into engagement with the material being baled, so as to be rotated by the movement of said material, and gearing connecting said spur wheel and said twisting wheels. 120

5. A wire tier for baling presses, including a plurality of wire-twisting wheels disposed in a plane transversely of the length of the press and each movable longitudinally of the press, a spur wheel extending 125 through one wall of the press into engage-

ment with the material being baled, so as to be rotated by the movement of said material, gearing connecting said spur wheel and said twisting wheels, and means for automatically throwing said gearing out of mesh.

5 In testimony whereof we have signed our

names to this specification in the presence of two subscribing witnesses.
